[57] CLAIM

The ornamental design for a combined light support and form for rounding out drapery into a columnar shape, as shown.

DESCRIPTION

FIG. 1 is a perspective view taken from the top of a combined light support and form for rounding out drapery into a columnar shape showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof.
